(57) **CLAIM**

The ornamental design for baked snack chip with irregular shape having notched edges, as shown and described.

DESCRIPTION

FIG. 1 is a top perspective view of a baked snack chip having notched edges, showing our new design.

FIG. 2 is a top plan view of the FIG. 1 embodiment.

FIG. 3 is a bottom plan view of the FIG. 1 embodiment.

FIG. 4 is a right side elevational view of the FIG. 1 embodiment.

FIG. 5 is a left side elevational view of the FIG. 1 embodiment.

FIG. 6 is a front elevational view of the FIG. 1 embodiment.

FIG. 7 is a rear elevational view of the FIG. 1 embodiment.

FIG. 8 is a top perspective view of a baked snack chip having notched edges, showing a second embodiment of our new design.

FIG. 9 is a top plan view of the FIG. 8 embodiment.

FIG. 10 is a bottom plan view of the FIG. 8 embodiment.

FIG. 11 is a right side elevational view of the FIG. 8 embodiment.

FIG. 12 is a left side elevational view of the FIG. 8 embodiment.

FIG. 13 is a front elevational view of the FIG. 8 embodiment.

FIG. 14 is a rear elevational view of the FIG. 8 embodiment. FIG. 15 is a top perspective view of a baked snack chip having notched edges, showing a third embodiment of our new design.

FIG. 16 is a top plan view of the FIG. 15 embodiment.

FIG. 17 is a bottom plan view of the FIG. 15 embodiment. FIG. 18 is a right side elevational view of the FIG. 15 embodiment.

FIG. 19 is a left side elevational view of the FIG. 15 embodiment.

FIG. 20 is a front elevational view of the FIG. 15 embodiment.

FIG. 21 is a rear elevational view of the FIG. 15 embodiment.

FIG. 22 is a top perspective view of a baked snack chip having notched edges, showing a fourth embodiment of our new design.

FIG. 23 is a top plan view of the FIG. 22 embodiment.

FIG. 24 is a bottom plan view of the FIG. 22 embodiment.

FIG. 25 is a right side elevational view of the FIG. 22 embodiment.

FIG. 26 is a left side elevational view of the FIG. 22 embodiment.

FIG. 27 is a front elevational view of the FIG. 22 embodiment; and,

FIG. 28 is a rear elevational view of the FIG. 22 embodiment.
